UNITED STATES PATENT OFFICE

2,383,384

METALLURGICAL INDUCTION FURNACE

James Coffee Harris, Jr., Philadelphia, Pa.

Application July 18, 1944, Serial No. 545,425

3 Claims. (Cl. 13—5)

This invention relates, generally, to electric metallurgical furnaces, and it has particular relation to furnaces of the horizontal open ring type, as disclosed in my Patent No. 2,079,610, issued May 11, 1937.

An object of the invention is to improve the operating characteristics of a furnace of this type, so that it is adapted to melt non-ferrous metals.

Another object of the invention is to increase the resistance of a portion of the secondary circuit over the balance thereof, formed by the metal being melted and refined.

A further object of the invention is to improve the power factor of such a furnace and to increase its efficiency in generating heat to melt and refine the metal.

Other objects of the invention will, in part, be obvious and, in part, appear hereinafter.

For a more complete understanding of the nature and scope of this invention, reference can be had to the following detailed description, taken together with the accompanying drawing, in which:

Figure 1 is a top plan view of a single phase furnace embodying the invention; and

Figure 2 is a detail sectional view taken along the line 2—2 of Figure 1.

Referring now to Figures 1 and 2, it will be noted that the reference character 10 designates the primary circuit or winding of the furnace which, it will be understood, is arranged to be connected to a suitable source of alternating current, such as a 60 cycle source. The primary circuit or winding 10 surrounds the central leg of a three-legged core or transformer 11 of laminated magnetic material of the kind used in ordinary transformer construction.

A generally rectangularly shaped furnace body 12 of suitable refractory material, extends through the windows of the core 11, and has formed therein a ring channel 13 in which the metal 14, to be melted and refined, is located. It will be understood that the metal 14 forms a part of the secondary circuit of the transformer into which current is induced by the primary circuit or winding 10 for the generation of heat to accomplish the melting and refining operation.

There is provided a charging chamber or hearth 15 which has an inclined wall portion 16 merging with the bottom wall of the ring channel 13. The purpose of this arrangement of the charging hearth 15 is fully set forth in the aforesaid patent.

A plug 17 serves to close a tap opening 18 55

through the bottom of the ring channel in the furnace body 12. It will be understood that the tap opening 18 can be located at any other convenient point.

5 The furnace construction herein described is particularly well adapted to melt and refine non-ferrous metals, such as aluminum, manganese, magnesium, copper, and alloys thereof. Such metals have low electrical resistance and high electrical conductivity. Because of this, the resistance of the secondary circuit, when formed only of such metals, is low and the current flow is relatively high, being limited only by the effective impedance of the transformer or furnace as a whole. As a result, the power factor of the furnace is relatively low and it cannot operate efficiently.

With a view to overcoming the foregoing difficulty, there is provided a resistor in series circuit relation with the secondary circuit formed by the metal 14 in the form of a block 20 of carbonaceous material, such as a molded carbon or graphite block. The block 20 is shown as completely choking the channel 13 in the charging hearth with its opposite sides in contact with the metal 14. It is preferably frictionally mounted in grooves to prevent it from floating on the molten metal. However, it may be held in place by any convenient means.

20 In order to start the furnace, a small charge of molten metal can be ladled into the channel 13, sufficient to complete the secondary circuit, with the resistor or block 20 forming a part. Alternatively, gas or oil jets (not shown) can be used initially to melt a small charge. Moreover, the furnace can be made self-starting if small pieces of the metal or powdered metal are used to complete the secondary circuit.

25 If the furnace is used principally for melting and refining aluminum, the refractory forming the furnace body 12 should have a high aluminum oxide (Al_2O_3) content.

30 While the invention has been disclosed in conjunction with a single phase furnace, it can be embodied in a three phase furnace such as that disclosed in Patent No. 2,079,610. In such a construction there would be provided a high resistance, conducting block or resistor, individual to each phase.

35 Since certain further changes can be made in the foregoing construction, without departing from the spirit and scope of the invention, it is intended that all matter shown in the accompanying drawing or described herein, shall be

interpreted as illustrative and not in a limiting sense.

What is claimed is:

1. In an electric, induction furnace of the horizontal open ring type, a high resistance electrically conducting block choking the ring channel and forming a portion of the secondary.
2. In an electric induction furnace of the horizontal, open ring type for melting and refining

metal, an electrical conducting member choking the ring channel and having an electrical resistance substantially higher than that of the metal being melted and refined.

3. In an electric induction furnace of the horizontal, open ring type for melting and refining non-ferrous metal, a member of carbonaceous resistance material choking the ring channel.

JAMES COFFEE HARRIS, Jr.
